Primary Examiner — Freda S Nunn(74) *Attorney, Agent, or Firm* — The Watson IP Group, PLC; Jovan N. Jovanovic; Vladan M. Jasiljevic(57) **CLAIM**

The ornamental design for a support sleeve for a bag in box package, as shown and described.

DESCRIPTION

FIG. 1 is a top perspective view of the support sleeve for a bag in box package showing the ornamental design;

FIG. 2 is a bottom perspective view thereof;

FIG. 3 is a front elevational view thereof;

FIG. 4 is a back elevational view thereof;

FIG. 5 is a first side elevational view thereof;

FIG. 6 is a second side elevational view thereof;

FIG. 7 is a top plan view thereof;

FIG. 8 is a bottom plan view thereof;

FIG. 9 is a bottom perspective view thereof showing the holding portions bent inwardly and a box being supported thereby; and,

FIG. 10 is a top perspective view thereof being installed over a box.

The dashed lines show features that form no part of the claimed design.

1 Claim, 10 Drawing Sheets(56)
